UNITED STATES PATENT OFFICE.

RENÉ LONGUE, OF PANTIN, FRANCE.

MEANS FOR LUBRICATING AND COOLING A SUBMERGED AND INSULATED ELECTRIC MOTOR.

Application filed March 7, 1921. Serial No. 450,361.

To all whom it may concern:

Be it known that I, RENÉ LONGUE, citizen of the French Republic, residing at Pantin, Seine, France, have invented certain new and useful Improvements in a Means for Lubricating and Cooling a Submerged and Insulated Electric Motor (for which I have filed an application in France March 4, 1920, Patent No. 511,071), of which the following 10 is a specification.

For the purpose of electrically and physically insulating an electric motor from surrounding media, it has been proposed to encase the latter in an insulating body of high 15 specific heat, and contained in an absolutely tight casing. In order, during operation of the motor, to permit the increase of the capacity of the casing when the insulating body (oil, for example) expands by reason 20 of the heat, use is made of pressure counter-balancing members formed of a flexible and deformable diaphragm and constituting a part of said casing. These arrangements are defective. In fact, the diaphragm which 25 forms the separating surface between the expandible insulating body and the surrounding medium is mechanically attached to the casing of which it forms a wall, so that its movements are limited either by said 30 attachment or by the deformation of the diaphragm. In any case the presence of said diaphragm introduces a heterogeneous element of certain characteristics and hence interferes with the pressure balancing, which 35 to be exact, should be purely hydrostatic.

The purpose of the present invention is to effect an exact balance between the pressure prevailing inside and outside of the casing; for this purpose all mechanical elements are 40 omitted from a certain surface between the surrounding medium and the insulating body, so as to permit the free expansion and contraction of the latter.

In the case in which the insulating liquid 45 used and the lubricating oil are to be separate, for example, when the potential is so high that the insulator is formed of transformer oil unsuitable for lubrication, the insulating oil and the lubricating oil are preferably enclosed in separate tight chambers, each of which is connected with the surrounding medium in the same manner and for the same purpose as previously indicated.

For this purpose each device adapted to 50 balance the pressures of the oil and of the

surrounding liquid is composed of two similar tight reservoirs placed at the same level, one of which communicates by its upper part with the chamber containing the oil and by its lower part with the other reservoir which 60 is open to the surrounding liquid at its upper part; the plane of contact between the surrounding liquid and the oil is preferably approximately aligned with a horizontal plane containing the rotor axis, while the 65 horizontal section of the reservoirs is sufficiently large so that the variations of the volume of the oils are transferred or removed by slight drops in level from the contact plane of the surrounding liquid and the 70 oil.

An exemplary embodiment of the invention is illustrated in the accompanying drawing.

Fig. 1 is a plan view partly in horizontal 75 central section on the lines 1—1 of Figs. 2 and 3.

Fig. 2 is a transverse sectional view on line 2—2 of Fig. 1, and

Fig. 3 is a similar view on line 3—3 of 80 Fig. 1.

In this exemplary form the electric motor, rotor and stator, are completely enclosed in a tight casing 1; the motor is not shown, for the sake of clearness, but the shaft of the 85 rotor is, however, indicated at 2. The casing 1 is completely filled with insulating liquid. On the other hand, in order to lubricate the parts subject to friction, the bearings 3, forming the supports for the ends of the 90 shaft 2 of the rotor, are placed in lubricating oil enclosed in two tight zones 4^a and 4^b. Two stuffing boxes 5 permit the passage of the shaft 2 from the closed chamber 1 containing the insulating oil into the chambers 95 4^a and 4^b containing the oil for lubricating the bearings 3, while separating the two oils.

If there is only a single shaft end, a stuffing box 6 permits its passage therefrom; where two shaft ends are used, another 100 stuffing box is provided at the opposite end.

The tight lubricating oil chambers communicate at their upper part with a tight reservoir 8 through conducting pipes 9 and 10, this reservoir 8 being in turn connected 105 by another pipe 11 to a similar reservoir 12, mounted in alignment to the first reservoir with respect to the horizontal plane containing the axis of the rotor. The reservoir 12 receives water or other liquid form- 110

ing the surrounding medium through the inlet 13. Two similar reservoirs 14 and 15 serve as balancing members for the insulating oil, the casing 1, which contains it, communicating with the reservoir 14 by the pipe 16, while the reservoir 14 communicates with the reservoir 15 through the pipe 17. The inlet 18 permits filling of the reservoir 15 with liquid surrounding medium.

10 These reservoirs are arranged so that the contact level M—M of the oil and the water in the reservoirs 8 and 14, is in a horizontal plane passing through the axis of the rotor, at ordinary temperature, so as to obtain a better balancing effect.

In addition, the horizontal section of the reservoirs is sufficiently large so that the variations in the volume of the oils is transmitted by very slight drops in level from 20 the plane of contact with the surrounding liquid.

Having now fully described the invention what is claimed as new and desired to be secured by Letters Patent is:

- 25 1. In a submersible electric motor, a casing adapted to contain a motor and filled with an insulating liquid, a surrounding liquid a conducting pipe terminating at one of its ends at the upper part of the casing, 30 the said pipe having a vertical portion, and opening at its other end on the surrounding liquid, the plane of junction between the insulating liquid and the surrounding liquid being in the vertical part of the pipe.
- 35 2. In a submersible electric motor, a casing adapted to contain a motor and filled with an insulating liquid, a surrounding liquid a conducting pipe terminating at one of its ends at the upper part of the casing, 40 the said conducting pipe having a vertical portion, and opening at its other end on the surrounding liquid, the plane of junction between the insulating liquid and the surrounding liquid being in the vertical part 45 of the pipe, bearings for the shaft of the motor, a casing containing each bearing and filled with lubricating liquid, a common pipe having a vertical part, and open at its lower end on the surrounding liquid, other pipes 50 connecting the upper part of each bearing casing with the upper ends of the said common pipe, the plane of junction between the

lubricating liquid and the surrounding liquid being in the vertical part of the said common pipe.

3. In a submersible electric motor, a casing adapted to contain a motor and filled with an insulating liquid, reservoirs located on both sides of the casing, a surrounding liquid in one of said reservoirs a pipe connecting the upper part of the casing with that of one of said reservoirs, another pipe connecting the lower part of the first reservoir with that of the second reservoir, this latter reservoir opening at its upper part on the surrounding liquid, the plane of juncture between the insulating liquid and the surrounding liquid being in the first reservoir and passing approximately through the axis of the rotor.

4. In a submersible electric motor, a casing adapted to contain a motor and filled with an insulating liquid, reservoirs located on both sides of the casing, a surrounding liquid in one of the reservoirs a pipe connecting the upper part of the casing with that of one of said reservoirs, another pipe connecting the lower part of the first reservoir with that of the second reservoir, this latter reservoir opening at its upper part on the surrounding liquid, the plane of juncture between the insulating liquid and the surrounding liquid being in the first reservoir and passing approximately through the axis of the rotor, bearings for the shaft of the motor, a casing enclosing each bearing and filled with lubricating liquid, two additional reservoirs located on the respective sides of the casing, a pipe connecting the upper part of one bearing casing with one of said last mentioned reservoirs, another pipe connecting the lower part of said last mentioned reservoir with the other of said last mentioned reservoirs, this other reservoir opening at its upper part on the surrounding liquid, the plane of juncture between the lubricating liquid and the surrounding liquid being in the first reservoir, and said plane passing approximately through the axis of the rotor.

In testimony whereof I have signed my name to this specification.

RENÉ LONGUE.
